UNITED STATES PATENT OFFICE.

HENRY C. EGERTON, OF RIDGEWOOD, NEW JERSEY, ASSIGNOR TO WESTERN ELECTRIC COMPANY, OF NEW YORK, N. Y., A CORPORATION OF ILLINOIS.

LOUD-SPEAKING TRANSMITTER.

1,111,253.

Specification of Letters Patent. Patented Sept. 22, 1914.

Application filed October 19, 1911. Serial No. 655,508.

To all whom it may concern:

Be it known that I, HENRY C. EGERTON, citizen of the United States, residing at Ridgewood, in the county of Bergen and State of New Jersey, have invented a certain new and useful Improvement in Loud-Speaking Transmitters, of which the following is a full, clear, concise, and exact description.

10. This invention relates to telephone transmission apparatus and has for its object, to provide a telephone transmitter for use in announcing or like systems in which a plurality of receivers are connected in circuit 15 to respond to current variations caused by the operation of a single transmitter.

A transmitter to operate efficiently in a system of this kind must be capable of being used on a circuit of any impressed voltage 20 and a type of transmitter well adapted to such use is one in which two or more granular carbon buttons or other resistance varying means are connected with the diaphragm by means of a lever arm so that the pressure, 25 upon the resistance varying material is simultaneously increased and decreased in the separate buttons by the operation of the diaphragm.

One of the features of this invention has 30 to do with the relation of the movement of the diaphragm to the button electrodes whereby the amplitude of the movement of the diaphragm is greatly reduced before it is transmitted to said buttons thereby eliminating undue distortion of the quality of 35 the transmission. This is accomplished by so pivoting the lever arm that the relation of the movement of the diaphragm to the movement of the electrode buttons is about 40 two to one. While this also decreases to a certain extent the quantity, this is made up in the increased current.

Another feature of this invention relates 45 to the mounting of the diaphragm, electrodes and connecting lever whereby the moment of the moving parts may be greatly reduced by locating the heavier parts near the center of oscillation and thereby having a small moment of inertia.

50. Another feature of this invention relates to the means provided for cooling the current carrying parts of the device and consists in providing water channels around the electrode buttons with means for attaching 55 a running water supply thereto.

Other features of the invention relate to the various details of construction, combination of parts and materials used for obtaining the desired results in the most efficient manner.

60. In the drawings Figure 1 is a vertical sectional view through the device illustrating the operating parts. Fig. 2 is a fragmentary detail view of the connecting lever and associated parts. Fig. 3 is a detail perspective 65 with parts broken away, showing the method of cooling the electrodes. Fig. 4 is a detail view showing the method of connecting the movable electrodes together and to the lever arm. Fig. 5 is a perspective with parts 70 broken away of the device assembled.

As shown in the drawings, 5 designates a supporting base or plate of circular form carrying a circular mounting ring 6, which is cut away to receive a diaphragm 7, which 75 is clamped thereto by means of a face plate 8. The face plate 8 may be screw-threaded for attachment of a transmitter mouthpiece 9. The diaphragm 7 is preferably formed of 80 glass as it is well known that a diaphragm of this material will respond much more accurately to sound waves than will one of any other known material. Said diaphragm is supported between soft rubber bushings or 85 tubes 10, 10, one located on either side thereof and clamped in place by the face plate 8. Supported upon the lower face of the supporting plate 5 is a lever comprising arms 13 and 14 of different lengths and a supporting member or web 15. The lever and web are 90 secured together preferably by spot welding as this insures against loosening of parts and consequent inefficient operation of the apparatus. The supporting member or web 15 is provided with a V-shaped groove 16 adapted 95 to receive conical shaped bearing pins 17, 17, which are secured in the lower face of said supporting plate 5. Secured to the web 15 upon opposite sides of the center thereof and extending in opposite directions are flexible supporting members 18, 18, the outer ends of which are secured to the lower face of the base 5 by means of screws. The members 18, 18, support the entire weight of the 100 lever from the other parts which may be connected therewith and at the same time permit sufficient freedom of movement of said lever arm to insure the efficient operation of the device. The arm 13 of said lever is attached to the diaphragm 7 while the 105

other arm 14 of said lever extends downwardly for attachment with transmitter buttons as will more fully hereinafter appear.

As shown in the drawings there is attached to the lower face of the plate 5 a supporting member comprising a web portion 25 and two laterally separated downwardly extending lugs 26, 26. These lugs are provided with aligned openings 27, 27, 10 each adapted to receive a metal button or cylinder 28. Each of these cylinders 28 has a chambered portion 29 adapted to receive an electrode 30 preferably of carbon attached to a metal stem or post 31 extending through an opening through said cylinder and screw-threaded on its end to receive nuts 32 and 33 for clamping said electrode 30 in place and for attachment of a terminal. Each electrode and stem is insulated from the walls of the cylinder 28 by means of an insulating bushing 34. Secured to the face of the cylinder 28 is a flexible metal electrode 35 preferably of 14 carat gold as such metal has been found 20 to be most efficient and responsive when operated in connection with the glass diaphragm. The electrode 35 is secured to the face of the cylinder 28 by means of a screw-threaded ring 36 which engages screw 30 threads on the periphery of said cylinder. Attached to one of said metal electrodes 35 is a screw-threaded stud 40 which when the metal cylinders 28, 28, are in place is adapted to pass through an opening 41 near 35 the end of the arm 14 of the lever and engage an interforly screw-threaded extension 42 on the other of said electrodes, thereby securing said electrodes together and to the lever arm 14. Set screws 43, 43, extending 40 through the walls of the lugs 26, 26, engage said cylinders 28, 28, to retain them in place. A resistance varying medium 45 such as comminuted carbon is placed in the chambers 29, 29, between the fixed and movable electrodes. The cylinders 28, 28, and lugs 26, 26, are made with plenty of metal in order that there will be a large surface for conducting the heat away from the chambers 29, 29, generated by heavy currents.

Additional means such as radiating plates may be supplied for conducting away the heat or the transmitter may be arranged for water cooling. In the drawings the latter arrangement is shown and consists in providing in the lugs 26, 26 channels 50, 50, which surround the cylinders 28, 28, and are connected with each other by means of other channels or pipes 51, 51, through the 55 web portion 25 which in turn may be connected with inlet and outlet pipes 52 and 53 of a suitable water supply. Screw-threaded retaining rings 54, 54, are secured to said lugs to retain water-tight coverings 60 55, 55, over said channels 50, 50.

The base plate 5 and the web 15 are secured together by means of nuts and bolts 60, 60, extending through insulating bushings 61, 61, such as ivory or like insulating material not susceptible to temperature or weather changes. A cover 62 is provided for the lower part of the apparatus which is slipped on from the bottom and secured to the plate 5. A circular plate 65 having an offset portion 66 therein to permit movement of the arm 13 is secured to the back of the mounting ring 6.

By using a glass diaphragm, which has been found to reproduce more faithfully than any other material all of the tones of the human voice, in combination with the electrodes of soft metal which have very little if any elasticity, the elasticity of all of the parts except of the diaphragm may be eliminated so that the diaphragm alone will take care of all of the vibrations without being influenced by counter vibrations of the electrodes or other movable parts. It has been found that by this means a very much better reproduction of the voice currents is obtained and particularly of the overtones of the voice.

I claim:

1. In a telephone transmitter, the combination with a glass diaphragm of carbon containing chambers, soft metal electrodes for said chambers responsive to the vibrations of said glass diaphragm and means for reducing the amplitude of the vibrations of said metal electrodes with respect to the amplitude of vibrations of said glass diaphragm.

2. The combination with a supporting base having an opening therethrough of a transmitter diaphragm mounted thereon, rigidly supported carbon containing chambers carried by said base, laterally separated movable electrodes in said chambers rigidly connected together, and a lever arm for connecting said diaphragm and said electrodes, said lever arm being pivotally supported upon said base and extending through the opening therein.

3. The combination with a supporting base of a transmitter diaphragm mounted thereon, carbon granule containers carried by said base, movable electrodes in said containers, a lever arm connecting said electrodes with said diaphragm, pivotal members for said lever arm carried by said base and flexible supporting members attaching said lever arm to said base.

4. The combination with a supporting base of a transmitter diaphragm mounted thereon carbon granule containers, movable electrodes in said containers, a lever arm connecting said electrodes with said diaphragm, pivotal supporting members for said lever arm carried by said base and flexible supporting members attached at one end

to said lever arm, said members being extended in opposite directions from said lever arm and having their outer ends attached to said base.

- 5. The combination with a supporting base having an opening therein of a transmitter diaphragm mounted thereon, carbon granule containers, supporting means for said containers attached to said base and having an opening therein in alignment with the opening in said base, a lever arm extending through said aligned openings and having one end connected with said diaphragm, movable electrodes in said containers, and means for connecting said electrodes with each other and with one end of said lever arm.
- 6. The combination with a supporting base having an opening therein, of a transmitter diaphragm mounted in said base, carbon granule containers, rigid supporting means for said containers attached to said base and having an opening therein, a pivotally supported lever having arms of different lengths extending through said openings the longer of said arms being attached

to said diaphragm, said shorter arm being provided with an opening near one end thereof, movable electrodes supported in said containers, a screw threaded pin on one of said electrodes passing through the opening in said arm and an interiorly screw threaded portion carried by the other of said electrodes to receive said pin.

- 7. The combination with a supporting base of a transmitter diaphragm mounted thereon, laterally separated supporting lugs carried by said base and having aligned openings therein, a metal cylinder adapted to be secured in each of said openings and having a chamber therein, movable and stationary electrodes carried by each of said cylinders and means for connecting said electrodes with said diaphragm.

In witness whereof, I, hereunto subscribe my name this 18th day of October, A. D., 1911.

HENRY C. EGERTON.
